SHOW CASE

Leo W. Kennedy, Detroit, Mich.

Application August 18, 1930, Serial No. 476,185

11 Claims. (Cl. 312—118)

This invention relates to show cases and more particularly to improvements therein tending to simplify and improve the same generally.

One of the primary objects of this invention is to provide means for removably supporting the lights of the show case at an inclination to the base thereof.

A further object of this invention is to provide a show case in which the number of connecting clips or brackets required is reduced to a minimum, and in which a limited number only of these connecting clips are visible from the front of the show case.

The invention further contemplates the provision of a sham for the show case and a novel means for holding this sham in position and the provision of a novel form of handle construction by which the show case may be moved from place to place.

Other objects and advantages of this invention will become more apparent as the following description proceeds, particularly when reference is had to the accompanying drawings wherein:

Figure 1 is a fragmentary perspective view of a show case constructed in accordance with the teachings of this invention;

Figure 2 is a transverse sectional view through the show case shown in Figure 1;

Figure 3 is a perspective view of a portion of the show case showing the parts thereof in spaced relation to each other;

Figure 4 is a fragmentary sectional view taken substantially on the line 4—4 of Figure 3;

Figure 5 is a perspective view of one of the shams used in connection with the show case; and

Figure 6 is a fragmentary sectional view through one corner of the show case showing the means for holding the sham in position.

Figure 7 is a fragmentary sectional view through a portion of the show case showing the means for clamping the lights.

Referring then particularly to the drawings wherein like reference characters designate corresponding parts throughout all views, there is illustrated in Figure 1 a show case 10 having the floor 11, end lights 12, front light 13 and narrow top lights 14 and 15. Supporting members 16 may be secured to the under side of the floor 11 to provide means for supporting the show case from a table or counter (not shown).

Fixed to the front and end edges of the floor 11 is a molding 17 and fixed to the rear edge of the floor 11 is a threshold 18. The latter is 55 slightly shorter in length than the rear edge of

the floor 11, for a purpose hereinafter to be more fully described, and a covering of monel metal 19 preferably extends from the molding 17 over the floor of the show case and over the threshold 18.

The present invention contemplates in particular the provision of means for removably supporting the front and end lights of the show case at an inclination to the base thereof. To provide for this, each section of molding 17 is provided in its upper face with a groove or recess 20 which is inclined at the desired angle to the base or floor of the show case. The lower edges of the panes of glass constituting the lights of the show case are positioned in the grooves 20 so that the lights extend from the molding at an inclination to the floor 11.

For yieldably retaining the edges of the lights in the grooves 20 there is mounted in each groove a continuous spring strip. Each spring strip is provided with a base portion 21 which overlies the base of the groove and with a side portion 22 which is return bent as at 23 to provide the free edge portion 24 which engages the inner side of the groove. Thus, when the lower edge of the light is positioned in the groove, the free edge 25 portion 24 of the spring strip engaging the side of the groove urges the portion 22 of the spring strip into firm engagement with the lower edge of the light. Thus the lights are yieldably retained in the grooves without the necessity of providing auxiliary retaining strips which must be removed before the lights can be removed.

To aid in supporting the adjacent edges of the end and front lights, there is provided a pillar 30 which is fixed at its lower end to the front corner 35 of the floor 11. The pillar 30 is provided with the faces 31 and 32 providing seats for the adjacent edges of the lights 12 and 13 respectively and is further provided at its upper end with the horizontally extending arm 33 which bisects the angle 40 between the front and end lights. The arm 33 provides a seat for the adjacent edges of the top lights 14 and 15 and this arm is preferably provided at its inner end with a raised portion 34 which is shaped to engage the inner edges of 45 the top lights, as clearly illustrated in Figure 1 of the drawings. A clip 35 fixed to the top of the post 30, as by the bolt or the like 36, engages the top, end, and front lights to hold these lights in engagement with their seats. It will be noted that the clip 35 is relatively small so that the amount of metal visible from the front of the show case is reduced to a minimum.

Fixed to the floor of the show case and at the rear corner thereof is a pillar 40 provided with 55

the portion 41 which is complementary to the threshold 18 in that it fits against the end of the threshold and projects toward the end of the show case for attachment to the end of the adjacent 5 molding strip, as designated by the reference character 42. The pillar 40 is provided with the inclined edge 43 which constitutes a seat for the rear edge of the end light 12 and is provided in its upper edge with a recess 44 of a depth sufficient 10 to receive, and of a width sufficient to support, the rear edge of the top light 14. A clip 45 is fixed to the top of the pillar 40 as by the bolt or the like 46 and engages the top light 14 and the end light 12 to hold these lights in engagement with their 15 respective seats.

To divide the interior of the show case into a plurality of compartments, partitions 50 are provided, these partitions being held in position by suitable supports designated by the reference 20 character 51. Arranged in each compartment is a sham such as illustrated in Figure 5 of the drawings and designated by the reference character 52.

Each sham is formed with a body portion having 25 the top wall 53 which preferably terminates at its rear edge in an upwardly extending flange 54. The front wall 55 of the sham extends downwardly at an angle from the top 53 and is provided at its lower edge with a flange 56 adapted to rest against the inner side of the molding 17, as clearly illustrated in Figure 2 of the drawings. The side wall 57 of the sham is inclined at an angle relative to the top 53 in the same manner as is the wall 55 and this side wall is provided at its 30 lower edge with a flange 58 similar to the flange 56. The sham is preferably formed in sections, one of which is slotted, as designated by the reference character 59, the other section of the sham being provided with apertures 60 adapted to register with the slots 59 so that bolts 61 may be passed 35 through the apertures and the aligned slots to secure the two sections of the sham to each other. A wing nut or the like 62 may be engaged with each bolt to clamp the sections of the sham against 40 movement relative to each other. By forming the sham in adjustable sections as illustrated, the width of the sham may be adjusted to the width of the compartment in which the sham is to be positioned.

50 Adjacent its side, the sham is provided with a rearwardly extending projection 65 and adjustably connected to this projection is an extension 66, the latter being provided with the slots 67 and the former being provided with the apertures 68 55 which are similar to the slots and apertures 59 and 60, respectively. The extension 66 is provided on its end with the flange 69, the lower end of this flange being cut at an angle to conform to the angle of the flange 58.

60 The end of the extension 66 is positioned in a recess 70 which is formed in the side face of the pillar 40. This recess is shaped to snugly receive the end of the extension, being provided with the inclined side 71 on which the inclined side wall 65 of the projection seats. The recess is further provided with the shoulder portion 72 on which the top portion of the extension seats and is sufficiently wide to receive the flange 69 of the extension. It will be obvious that the extension 66 may 65 be adjusted relative to the body of the sham to a position where its end will engage the floor of the recess 70. Thus the end of the extension will be firmly seated in the recess 70 so that the pillar 40 provides means for not only supporting the end and top lights but provides means

also for positioning the sham 52 and for holding this sham in position.

The invention further contemplates the provision of handles 80 by which the show case can be moved. Each handle is provided with a grip portion 81 adapted to normally lie in a recess 82 formed in the outer face of the molding 17. Each handle is also provided with the leg portions 83 which extend into bores formed in the molding and to the ends of which nuts 84 are fixed. To 10 provide for a limited movement of the handle, counterbores 85 are provided in the molding strip, the nuts 84 being positioned in these counterbores. Thus the normal position of the handle is as illustrated in Figure 4 of the drawings, with the grip portion thereof flush with the outer surface of the molding. When it is desired to move the show case, the handles may be grasped and moved to a position limited by engagement of the nuts with the bases of the counterbores, in which the 15 grip portions of the handles will be spaced from the outer surface of the molding. Obviously, the handles will return to their normal inoperative position whenever they are released.

From the above it will be apparent that the 20 invention provides a show case in which the end and front lights are removably held in inclined position relative to the floor of the show case. Thus the lights may be readily removed without the necessity of disassembling the structure which 25 provides the grooves for the lower edges of the lights. The lights of the show case will be supported in position without, however, necessitating the utilizing of a plurality of metallic clips which are visible from the front of the show case, and the sham will be held in position by a portion of the structure which supports the end and top 30 lights of the show case.

While the invention has been described with some detail it is to be understood that the description is for the purpose of illustration only and is not definitive of the limits of the inventive idea. The right is reserved to make such changes in the details of construction and arrangement of parts as will fall within the purview of the attached claims.

What I claim as my invention is:

1. In a show case construction, a pillar having a recess in its side, a sham having a body portion and a projection formed adjacent one side of said body portion, and a member adjustably connected to said projection and forming an extension of the same, said member having an end portion engaged in said recess.

2. In a show case construction, a sham having an extension portion provided with an inclined side wall and a shoulder adjacent the upper end of said wall, and a pillar having a recess shaped to receive the end of the extension portion of said sham.

3. In a show case construction, a base, a molding secured to said base, end and front lights mounted in said molding and inclined relative to said base, a pillar projecting upwardly from said base in the angle between the adjacent edges of said end and front lights, said pillar having edge portions providing seats for the adjacent edges of said lights and having a horizontally extending arm fashioned with a recess in its upper edge, a pair of top lights having adjacent edges seating in said recess, and a clip fixed to said pillar and engaging said front, end and top lights to secure the same thereto.

4. In a show case, a base, means providing an upwardly opening groove adjacent said base and

arranged at an inclination to said base, a light having its lower edge disposed in said groove, and a spring strip disposed in said groove and having a return-bent portion disposed between the lower side of said groove adjacent the free edge thereof and the adjacent portion of the front light.

5. In a show case construction, a sham having top and side walls connected together, and a pillar forming a structural element of the show case and having a recess for receiving the ends of said top and side walls for holding said sham as a unit in position within the show case.

10. In a show case construction, a sham having top and side walls connected together, means providing an extension for said top and side walls, and a pillar forming a structural element of the show case and having a recess for receiving the said extension for holding said sham in position

20 within the show case.

15. In a show case construction, an end light, a top light, a pillar having a side edge forming a seat for said end light and having a top edge forming a seat for said top light, said pillar also having a recess in one side thereof and a sham insertable as a unit into the show case and having an end portion engageable in the recess aforesaid in the pillar for positioning the sham as a unit relative to the interior of the show case.

8. In a show case construction, a top light, a sham insertable as a unit into the show case, and a pillar having a recess formed in its upper edge providing a seat for the top light and having a second recess in its side for receiving an end portion of the sham to position the latter within the show case.

9. In a show case construction, a sham having a front wall and a side wall secured to the front wall to form a unitary construction insertable as a unit into the show case, and means including an upright of the show case structure for holding said sham in position within the show case.

10. In a show case construction, a sham having extensible front and side walls connected together to form a unitary construction insertable as a unit into the show case, and means forming a part of the show case structure for holding said sham in position within the show case.

11. In a show case construction, a sham having front, side and top walls connected together to form a unitary construction insertable into the show case as a unit, and a pillar forming a structural element of the show case cooperating with a portion of the sham to support the latter in position within the show case.

LEO W. KENNEDY.
